BRAUN TUBE

Kurt Schlesinger, Berlin, Germany

Application May 13, 1933, Serial No. 670,819
In Germany May 14, 1932

8 Claims. (Cl. 250—27.5)

In the production of Braun tubes and the like the problem frequently arises of concentrating or preliminarily concentrating to such extent a bundle of electrons (cathode ray), 5 which emerges from a shutter aperture, that after-focusing is rendered possible on full scale, for example by means of an electron-optical system (for example, in accordance with the German patent . . . (R. 84 555 VIIIa/21a1)).

10 According to the invention, there is produced for this purpose, between the outlet aperture for the cathode ray and the point raised to a high positive potential on to which the ray is to be concentrated, a field, the strength of which 15 diminishes from the outside towards the inside, i. e., towards the outlet aperture for the electrons.

Upon entering a field of this nature there will be acted upon to the least extent those 20 electrons which move in an axial direction, i. e., towards the anode, and to the greatest extent those electrons the directional angle of which is greatest in relation to the central path, i. e., those electrons which emerge from the outlet 25 aperture at a relatively large lateral angle. In this manner it is possible to concentrate in preliminary fashion all or at least practically all electrons emerging from the aperture, to such extent as to ensure proper focusing by means 30 of an after-connected electron-optical system without disturbing effects of a subsidiary kind, such as produced by those electrons which are not brought under the control of the electron-optical system.

35 According to the invention, the concentration field formed pursuant to the invention may be produced by means of semi-conductors. The invention may be more fully understood from the appended drawing, whereof

40 Fig. 1 shows schematically the arrangement according to the invention, whilst in

Fig. 2 a Braun tube furnished with a circular ring consisting of semi-conductive material is shown, and

45 Fig. 3 is a Braun tube, wherein a semi-conductor is provided which possesses the form of a conical tube.

In Fig. 1, 1 is a shutter having the aperture 2, through which there emerges the bundle of 50 electrons (electron outlet aperture). The shutter 1 is preferably constructed in the form of a circular ring, and furnished with a highly ohmic resistive coating 3 on the side directed towards the anode. At the outer periphery of the circular ring there is conducted to the resistive coat-

ing a suitably selected high negative bias (for example 500—1000 volts), whilst the inner edge at the outlet aperture possesses, in comparison with the ray, a suitably selected and preferably weakly positive potential. 7 is the anode, which is raised to a suitably selected, high positive potential in relation to the ray, and 6 a screening means, the potential of which is selected in such fashion that the upward point of the field situated between the resistive coating 3 and the anode 7 coincides approximately with the centre point of the anode. Owing to the drop in potential occurring in the resistive coating along the diameter of the circular ring, it is accomplished that the strength of the field decreases 15 from the outside towards the inside in the manner necessary according to the invention.

In Fig. 2 there is shown a suitable form of embodiment of a semi-conductive perforated shutter in conjunction with screening electrodes. A stream of electrons passes from a cathode 1 having a relatively large surface to a metallic shutter 2 without concentration, i. e., with a certain dispersion. The dispersion may certainly already be reduced, preferably by 25 means of a Wehnelt cylinder 9, but it is impossible with 9 and 2 alone to obtain from a large-surface cathode 1 a small focal point on the luminous screen. The arrangement 9, 2 does not cover in lenticularly exact fashion 30 bundles of rays with large dispersion and expanse. The efficiency of the same is greater in the arrangement described in the following.

The potential between 2 and 1 is positive and relatively small, for example about +200 volts. 35 The problem resides in focusing of all paths of electrons on a remotely arranged screen image point 3. This is only possible if the rays of the bundle 4 wandering to the greatest extent are deflected to the greatest degree towards the centre. According to the invention, this is accomplished by the stated semi-conductive shutter 5. The inner edge of a disc of mica coated with a resistive substance possesses the potential of the screening shutter 2, 45 whilst the outer edge on the other hand is raised to a preferably variable and strongly negative potential of, say, (-100)—(-500) volts. This is possible because the shutter 5 possesses a large radial resistance, and therefore merely 50 a weak current traverses despite the large difference in potential between the inner and the outer edge said current flowing from the inner to the outer edge of said electrode. The outer edge of disc 5 is supplied with the negative bias 55

through the lead attached to the lower end of said disc. This lead is connected to the one pole of a suitable potential source which is not indicated in the drawing, and the other pole of which is connected with the anode 2 which in turn is connected to the inner edge of the disc 5. Shutters of this nature may be produced in ready fashion. This actual main anode is the metallic shutter 6, which is furnished with a very small hole. From the edges of this hole there proceed to the shutter 5 field lines with concentrically conical inclination having the particularly advantageous property that the strength of field on these lines is all the greater the more remote the same are from the axis of the ray, because their path integral, measured in relation to the outer edge of the semi-conductive shutter 5, must be a few hundred volts greater than in relation to the inner edge. Experiments conducted by the applicants have shown that with an arrangement of this kind a very good concentration effect may be obtained, and that in this connection it is possible to suitably adjust the "focus" of the system 2, 5, 6 by selection of the potential of the outer edge, and even more that this focus is only varied to an inessential degree upon variation in the first attraction potential between 1 and 2. The method, therefore, is suitable for use in television tubes with light control. According to the invention, there may also be employed screening walls 7 to avoid the effect of external fields, which walls may possess approximately the potential of the first anode 2 or the inner edge respectively. It may be accomplished by a screening means 8, which leaves merely a small ring of the high potential anode uncovered, that the latter acts virtually with merely a very small opening corresponding with the small reciprocal of 8. The screening means are preferably linked up with a potential, which corresponds with that of the preliminary anode or that of the inner edge of the highly ohmic of semi-conductive plate. Naturally the spacing between 5 and 8 is open to considerable variation in close connection with the potentials employed, and also the radial distribution of the field may be acted upon systematically by applying the resistive substance to the circular shutter 5 not in constant fashion, but in certain fashion to a greater degree on the inside or the outside.

The following arrangement (see Fig. 3) is also on the same basis. A large-surface cathode 1 is situated at the entrance of a conical tube 15. The tube is made from a semi-conductive material, or is coated with a material of this nature on the inside and is otherwise insulatory. It is possible, therefore, to build up between the closing rings 2 and 10 of this tube a difference in potential which, with suitable production of the tube resistance, may readily amount to a few hundred volts. It may then be observed that a large number of the field lines run parallel to the walls of the tube, and there is accordingly an excellent possibility of producing in positive fashion a defined converging acceleration field of cylindrically symmetrical kind. A preliminary concentration of the bundle of rays is rendered possible from the large-surface cathode 1 with the assistance of a "condenser" of the Wehnelt cylinder 9 to approximately -50 volts, so that the bundle of rays already enters the metallic shutter 2 with a divergence which is no longer of an excessive kind,

and it is accomplished within the semi-conductor tube 15, the form of which is suitably selected and may even be determined, that the electrons at the exit of the tube possess components of such nature directed radially inwards that the same all meet at the one point 3 on the luminous screen 11. Naturally, this electron-optical unit, the semi-conductor tube 15, may also be combined in many different ways with other arrangements of a known kind. Behind the same, for example, there may be provided an after-acceleration anode 6 raised to correspondingly higher potential, and the like. Light control may also take place, for example before the entry into the shutter 2, at the Wehnelt cylinder 9, or also otherwise, in the manner known per se, without variation in the optical conditions, as the same are rigidly determined by the semi-conductor tube 15. An advantage of the arrangement is also to be regarded in the fact that the optical axis, with suitable length of the tube 15, is very well defined, and owing to the large aperture of this optic is not varied even if on account of inexact centering of the Wehnelt cylinder 9 upon the light control small lateral movements of the bundle of rays take place at the commencement.

The invention is of particular importance for Braun tubes with a hot cathode. The same may be used with advantage in the case of tubes having a gas filling, but is also of advantage in connection with high-vacuum cathode ray tubes. The tubes may naturally be furnished in the known manner with one or more pairs of plates, in accordance with the purpose of use, and may also contain additional elements necessary for particular purposes, and more particularly deflecting or concentration electrodes for controlling the intensity of the cathode ray (for example, for television purposes).

I claim:

1. A Braun tube for television purposes comprising a hot cathode, an anode, means to control, means to deflect the cathode ray and a fluorescent screen, means for concentrating the cathode ray, said means comprising an electrode consisting of semi-conductive material, being arranged between said cathode and said anode.

2. A Braun tube comprising a plate-shaped indirectly heated cathode, an anode, means to control, means to deflect the cathode ray, a fluorescent screen, and a plate-shaped electrode of semi-conductive material furnished with an opening, said electrode being arranged in the path of the cathode ray between said cathode and said anode.

3. A Braun tube comprising a plate-shaped indirectly heated cathode, an anode, means to control, means to deflect the cathode ray, a fluorescent screen, and a plate of insulating material furnished with an opening and arranged in the path of the cathode ray between said cathode and said anode, the side of said plate of insulating material directed to the anode being coated with a material of a high ohmic resistance, the outer edge of said coating being adapted to be connected with the negative pole, and the inner edge of said coating being adapted to be connected with the positive pole of a potential source.

4. A Braun tube comprising a plate-shaped indirectly heated cathode, an anode, means to control, means to deflect the cathode ray a fluorescent screen, a plate-shaped metallic electrode furnished with an opening arranged between

- 5 said cathode and said anode, a plate-shaped element of insulating material furnished on its one side directed to the anode with a material of a high ohmic resistance, said insulating element arranged between said metallic electrode and said anode and a further plate-shaped metallic electrode furnished with an opening arranged between said semi-conductive element and said anode, said further electrode being 10 connected with the first said one.
- 10 5. A Braun tube comprising a plate-shaped indirectly heated cathode, an anode, means to control, means to deflect the cathode ray, a fluorescent screen, and an electrode of a truncated hollow conical form consisting of poorly 15 conductive material, said electrode arranged between said cathode and said anode, the end of said electrode directed to the anode adapted to have a high positive potential applied thereto.
- 20 6. A Braun tube comprising a plate-shaped indirectly heated cathode, an anode, means to control, means to deflect the cathode ray, a fluorescent screen, and an electrode of a truncated hollow conical form consisting of poorly 25 conductive material, said electrode arranged between said cathode and said anode, the end of

said electrode directed to the anode being adapted to have a high positive potential applied thereto, the conical base of said electrode being directed towards said anode.

7. A Braun tube comprising a plate-shaped indirectly heated cathode, an anode, means to control, means to deflect the cathode ray and a fluorescent screen, a metallic electrode adapted to have a positive potential applied thereto, arranged between said cathode and said anode, an 10 electrode adapted to have a negative potential applied thereto at least partly consisting of a material of high ohmic resistance arranged between said electrode and said anode, and a cylinder adapted to have a positive potential applied thereto furnished at its end directed to the anode with a shutter furnished with an opening surrounding said two electrodes.

8. A Braun tube comprising a cathode, an anode, a picture receiving screen, two pairs of 20 deflecting plates for scanning said screen, and means for concentrating the cathode ray, said means including an electrode consisting of semi-conductive material, said electrode being arranged between said cathode and said anode. 25
